WITNESS:

UNITED STATES PATENT OFFICE

ROSCOE TRACY BURROWS, OF BARRE, VERMONT

DESIGN FOR A DISPLAY CABINET

Application filed March 2, 1931. Serial No. 38,909. Term of patent 14 years.

To all whom it may concern:

Be it known that I, ROSCOE TRACY BURROWS, a citizen of the United States of America, residing at Barre, in the county of Washington and State of Vermont, have invented a new, original, and ornamental Design for Display Cabinet, of which the following is a specification, reference being had to the accompanying drawings, forming a part hereof.

I claim:

The ornamental design for display cabinet, as shown.

ROSCOE TRACY BURROWS.
